UNITED STATES PATENT OFFICE

CHARLES HARRY FISCHER AND FREDERICK H. FISCHER, OF CINCINNATI, OHIO

AUTOMATIC FORMING MACHINE

Application filed December 17, 1927. Serial No. 240,754.

Automatic forming machines to which our invention relates employ a series of tools which coact in sequence with the work for performing various cutting operations on metal. The term automatic forming machine is herein employed in its broader sense, and includes automatic screw machines and machines of the same general character. The tools are usually mounted in sequence upon a turret which rotates intermittently for placing the respective tools sequentially in coactive position with relation to the work. Reciprocating movements are also imparted to the respective tools, the durations of 10 actions between the tool and the work and the lengths of the reciprocations being determined respectively by the amount of metal removed from the work at each relative rotation between the tool and the work, and 15 the distance the tool is moved with relation to the work.

The tool-turret is mounted on a turret-slide which is reciprocated for the purpose of moving the respective tools toward and from the work. The turret-tools operate upon the work in directions lengthwise of the axis of the work. The turret-slide is also herein referred to as the end-slide and the tools thereon as the end-tools. In such machines there 20 is also usually a cross-slide at each side of the work, on which tools are mounted which coact with the work by being reciprocated in crosswise direction with relation to the work. The tools at the respective sides of the work 25 act upon the work in sequence, for instance, for providing the periphery of the work with contours according to the shapes of tools on the cross-slides and for cutting off the piece finished by the machine.

Endwise feeds of the material take place for repetitions of the operations to produce subsequent pieces of work. The feed of the work and its stoppage are also automatic. Means are also provided for rotating the 30 work, which rotation may be in one direction, or reverse rotations may be imparted to the work, and in some instances rotations are imparted to selective tools, depending on the character of cutting to be done by the tools. 35

The old type of machine of this character

which is now in general use is aptly illustrated in United States Letters Patent No. 604,306, granted W. S. Davenport, assignor to Brown & Sharpe Manufacturing Company, May 17, 1898, for metal screw machine. 55

In machines of this character it has been heretofore usual to control the endwise movements of the turret-slide by means of an integral cam, on which lobes were formed which respectively controlled the successive 60 movements of the turret-slide toward the work for durations and for distances determined by the cutting which the respective tools were to perform upon the work.

Assuming that six endwise operations were 65 to be performed upon the work, that is to say, assuming a turret provided with six tools and arranged to intermittently rotate for six positions of the turret, so that the six tools operate in sequence upon the work, it has 70 been customary to provide a cam with six cam-lobes integral thereon for each object to be formed by the machine. These cams are very expensive to make and if, in the making of the cam, any one of the lobes should be 75 incorrect, or if it should be desired to change the cutting done by any one of the tools either in duration or length, a change in the lobe of the cam controlling said tool would be required, which would necessitate the making 80 of a complete new cam with the six lobes integral thereon.

Furthermore, in machines of this character the durations of intermittent rotations of the turret are constant, while speed change 85 mechanism is provided for selected speeds of rotation of the cam. The multi-lobed cam is provided with a cam portion for each retraction of the turret-slide, by providing a low point or depression in the cam between each 90 pair of lobes. These depressions in the cam extend throughout such angle in the cam as to permit intermittent angular rotation of the turret, and this angle is computed upon the basis of the selected speed of rotation of the 95 cam which determines the speed of successive operations of the series of tools for performing the work, a piece of the work being completed at each rotation of the cam. The angular distances in the circle of rotation of the 100

cam occupied by the respective lobes is based upon a predetermined desired speed of rotation of the cam for finishing a piece of work within a given time.

5 If now it should be found that, by reason of change in material being operated on, or for other reason, the work could be performed more rapidly and that more pieces could be produced per hour by speeding up 10 rotations of the cam, such speeding up of rotation of the cam has disarranged the relation between duration of rotation of the turret at its constant speed and the speed of rotation of the tool-moving cam, because the 15 depressions in the cam reserved for duration of rotation of the turret at constant speed were no longer of sufficient angular extent at the increased speed of the cam.

It has therefore been found heretofore that 20 such an integral cam when once made could not have its rotations speeded up, because it disarranged the relation between the rotations of the turret at constant speed and the reciprocations of the turret-slide at new increased 25 speed, with the result that the angular distance of rotation of the cam originally reserved for turret rotation was, at the increased speed of rotation of the cam, no longer sufficient to complete the angle of rotation 30 of the turret and proper presentation of the next tool in proper position to the work, which made the cam useless for such increased speed, and necessitated the making of an entirely new cam for increased speed of 35 operation upon the work.

These methods of operation, which have heretofore been the usual practice, have been 40 very expensive, have limited output of the machines, and have made the use of a machine of this character prohibitive for many classes of work, and prohibitive in cost unless great numbers, amounting to a great many thousands, of the same article were to be produced in succession.

45 It is rapidly becoming the policy however for customers to order the products of machines of this character in small lots, largely on account of frequent changes in manufactured products, so that long runs of machines 50 of this character in continuously producing large quantities of the same article are becoming rather infrequent, making the operations of machines of this character rather expensive.

55 It is the object of our invention to provide new cam mechanism in machines of this character, and to segregate the cams controlling the various reciprocations of the tool-slide so 60 as to independently determine the duration and distance of movement for each tool desired; further, to provide for permitting change in relation between the cutting movements of the various tools; and, further, to 65 provide for permitting change in angular re-

lation between lobes to permit increased speed of rotation of the cam.

It is the object of our invention further, to 70 separate the lobes of the cam so as to have independent cam-lobes for the various operations; further, to provide a series of separate cam-lobes having cam-faces which are graduated in successively increasing distances of angular cooperation with the tool-slide for 75 successive increases in durations of tool movements, and are also graduated in successively increasing radial distances or rises for successively increasing lengths of reciprocations of the tools; and, further, to so arrange and relate these separate cam-lobes 80 that they act in sequence upon the respective tools for successive operations of the tools upon the work, and for change of angular relation between the lobes for proper rotations of the turret at constant speed, so that each 85 successive tool is properly positioned with relation to the work before coaction between the tool and the work takes place.

Our invention further contemplates the provision of proper preformed separate 90 cam-lobes, arranged in series, for coordinate assembly for producing a composite cam of desired form, dependent on the number of tools or turret movements, and the desired durations and distances of movements 95 of the respective tools, and for ready change of any of said elements by exchange of cam-lobes, for correction or desired change in durations or depths of cuts, and for desired change in angular relation between the cam-lobes 100 for permitting change in speed of rotation of the cam, regardless of intermittent movements of the turret at constant speed.

It is the object of our invention further 105 to provide improved relations of separate cam-lobes, and means for assembling the same; further, to provide novel means for assembling the cam-lobes in angular relation and for changing such angular relations; further, to provide for interchangeability 110 between cam-lobes for endwise movement of the end tool-slide and for crosswise movement of the cross tool-slide; and, further, to provide novel means for changing angular relations between cam-lobes for the cross-slides. 115

The invention will be further readily understood from the following description and claims, and from the drawings in this application.

We have exemplified our invention in connection with an automatic screw machine employing an endwise slidable tool-slide, on which a turret is mounted for presenting the various tools serially to the work, and employing cross-slides for coaction of tools in crosswise directions with relation to the work, although it is obvious that our invention is applicable to other machines, and the machine exemplified is to be understood as 120 125 130

a mere mechanism embodying our invention.

We have further exemplified our invention in connection with a given range of work, that is, diameters of work and durations, speeds and lengths of cutting operations, and it is understood that the application of our invention may be extended so as to include greater diameters and other durations, speeds and lengths of cutting operations.

10 In the drawings:

Fig. 20 is an exemplification of end cam-lobes, imposed on an angular scale, with the clamp-nut removed.

60 Fig. 21 is an exemplification of a side cam-lobe used for forming, imposed on an angular scale, and mounted on its shaft, the shaft being shown in cross-section on the line 21—21 of Fig. 10.

65 Fig. 22 is an exemplification of a side cam-

lobe used for cutting off, imposed on an angular scale partly broken away, the cam-lobe being shown mounted, its shaft being shown in section on the line 22—22 of Fig. 10.

Fig. 23 is a further exemplification of end cam-lobes imposed on an angular scale, the clamping nut being removed.

Fig. 24 is an exemplification of a series of threading cams imposed one on the other.

Fig. 25 represents a tabulation of the threading cams.

Fig. 26 is a still further exemplification of end cam-lobes imposed on an angular scale, the clamping nut being removed.

Fig. 27 is a further exemplification of a side cam-lobe used for forming, imposed on an angular scale and shown similarly to Fig. 21.

Fig. 28 is a further exemplification of a side cam-lobe used for cutting off, imposed on an angular scale, and shown similarly to Fig. 22.

Fig. 29 is a tabulation of an exemplifying series of cam-lobes arranged in steps of angular distances and of rises.

The frame 21 supports an end tool-slide 22, which is reciprocated back and forth on guides 23 on the frame. The tool-slide supports the tool-turret 24, which is journaled in a bearing 25 on the slide. (Figs. 1 to 5). The turret is provided with tool holding means 26, of which six are shown, arranged equidistantly in angular relation about the axis of the turret. (Fig. 13). Tools are fixed in these tool holding means. Six of these tools are shown. The number and kind of tools may vary, dependent on the work, and the number of tool holding means on the turret may also vary, according to the desired capacity of the machine. The turret is rotated intermittently to present the tools sequentially to the work for sequential coaction with the work in order to perform successive operations upon the work.

Suitable means are provided for intermittently rotating the turret and permitting the turret to rest in its respective angular positions for coactions of its respective tools with the work. The means for rotating the turret and holding the turret in work positions may be of suitable or usual construction.

The intermittent rotations of the turret are in the present exemplification caused by a driven disk 31 having a pin 32 thereon. The pin is arranged to operate in radial slots 33 in a disk 34 fixed to the turret-spindle 35 for rotating the turret one-sixth of a revolution at each rotation of the driven disk 31.

The material operated on may be such as is usually operated on in a machine of this character, and is exemplified as a metal rod 36, for instance, a solid round brass bar, which is passed intermittently through a quill-spindle 37, and is automatically fed intermittently

through said spindle by suitable mechanism, not more particularly described because well-known, and intermittently held in a suitable collet-chuck 38, in said spindle while being operated on by the respective tools, such 5 chuck being not more particularly described because well-known. The spindle is arranged to be rotated for rotating the work, as by means of pulleys 39, 40, which rotate in opposite directions, or at different speeds, according to the character of work, suitable clutch means being provided for imparting 10 any of said rotative effects to the spindle.

Cross tool-slides 41, 42, are arranged to 15 reciprocate crosswise of the material in guides 43, 44, on the frame. (Fig. 7.) These cross-slides are provided with tool-holders 45, 46, crosswise adjustable in suitable manner on the cross-slides, and arranged for receiving 20 tools 47, 48, rigidly connected therewith for coaction with the material by lateral movements of the cross-slides with relation to the material. Such tools are usually tools for forming the periphery of the material, and for cutting off the finished object from the 25 rod of material, the rod being then automatically fed axially for presenting a new portion thereof for coaction with the tools.

The means for moving the tool-slide 22, 30 also herein called the end-slide, comprise a lever 51 pivoted on a cross-rod 52 fixed in the main frame. (Fig. 5.) These means advance the end tool-slide in cutting direction. This lever has on it a segment-rack 53 which 35 meshes with a toothed rack 54 on the turret-slide. A cross-shaft 55 has a cam 56 rotatively fixed thereto. The cam coacts with a roller 57 rotating on an axle 58 fixed in bearings 59 of a fork 60 of the lever 51.

The turret-slide comprises the sections 61, 40 62. The toothed rack 54 is on the section 61. A crank-disk 63 is journaled in the section 62. A link 64 is articulated at one end on a pin 65 in the section 61 and at its other end is articulated 45 with the crank-pin on the disk 63. When the end-slide is in extreme cutting position, the swinging end of the lever 51 is 50 against the frame at 66, forming an anchor for the section 61 of the turret-slide. The crank-disk 63 is thereupon rotated a single 55 rotation by usual means, which positively withdraws the section 62 away from the material and positively draws the tool away from the work, the section 61 being meanwhile retracted by the action of the segment lever 51 for again straightening the link 64 to normal position.

A spring 67 located in a bore 68 in the frame 60 normally retracts the tool-slide and maintains the roller 57 in contact with the cam 56. The spring coacts with a plunger 69 in the bore 68 for pushing the plunger normally outwardly. The plunger is provided with an annular groove 70 in which a pin 71 is received, the pin projecting rigidly from the

section 61 of the end tool-slide through a slot 72 in the wall of the bore 68, for imparting movements of the plunger induced by the spring to the tool-slide for retracting the latter.

Means for advancing the cross-slides toward the work are exemplified as levers 75, 76, pivoted on a pivot-rod 77 fixed in bearings 78 in the frame. The outer ends of said levers are provided respectively with rollers 79, 80, journaled on pins 81, 82, fixed in bearings 83, 84, respectively in forks 85, 86, on the outer ends of said respective levers. (See Figs. 1 and 7.)

The lever 75 is provided with a segment-gear 87 which meshes with a toothed rack 88 on the cross-slide 41. The lever 76 is provided with a segment-gear 89 which meshes with a segment-gear 90 on a lever 91 journaled on a rod 92 fixed in bearings in the main frame. The lever 91 is provided with a segment-gear 93 which meshes with a tooth rack 94 on the cross-slide 42. Similar movements of the outer ends of the levers 75, 76, cause movements in opposite directions of the cross-slides 41, 42, toward the work.

The cross-slides are normally retracted away from the work respectively by springs. One of these springs is shown in Fig. 8 at 95, located in a bore 96. A sector of the wall of the bore is formed in the guideway on which the cross-slide slides, the remaining portion of said wall being formed in the cross-slide. One end of the spring bears against the end wall of the part of the bore in the guideway and the other end of the spring bears against a clip 97 secured to the cross-slide. The springs normally retract the cross-slides in opposite directions away from the work.

Cam-lobes 101, 102, mounted on a shaft 103 journaled in bearings 104 of the main frame control the movements of the respective cross-slides toward the work.

The intermittent turret rotations and the rotations of the cams are effected through the medium of a drive-shaft 105, journaled in bearings 106 in the main frame, and having a pulley 107 thereon. Suitable clutch mechanism 108 suitably operated connects the pulley with the drive-shaft. The rotations of the pin-disk 31 are effected when it is automatically connected with the drive-shaft by means of a suitable clutch 109 automatically operated by usual control means. The intermittent rotations of the turret are effected by means of the drive-shaft 105. The speeds of such intermittent rotations are constant, and are not affected by the speed change gearing mechanism located between the drive-shaft and the cam-shafts which control the tool-slide reciprocations.

This speed changing mechanism is shown generally as change-gears 110, between the shaft 105 and a shaft 111, journaled in a bearing in the main frame and having a worm

112 fixed thereto. The worm 112 meshes with a worm-wheel 113 fixed to a cross-shaft 114 journalized in a bearing in the main frame. The shaft 114 has a bevel-gear 115 fixed thereto, which meshes with a bevel-gear 116 fixed to the cam-shaft 103 which carries the cams for the cross-slides.

5 This shaft 114 has a gear 117 fixed thereto, which meshes with a gear 118 fixed to the cam-shaft 55, which carries the cam 56 for endwise movements of the turret-slide. The speeds of rotation of the cam-shafts may be changed by means of the speed change gearing.

10 In machines of this character, as heretofore constructed, the cam 56 has been an integral cam, having thereon the desired number of lobes integral with each other and located in the same plane, causing the successive desired 20 endwise movements of the turret-slide, each of such cams being cut for the specific work to be performed and the lobes thereof being integral with the cam and each of the other lobes thereon. Each cam, therefore, was a 25 fixed cam, having each contact-portion thereof, which coacts with the roller for operating the end-slide, fixed with relation to every other such contact-portion of the entire cam, and these contact-portions were definitely related angularly to form the depressions in 30 the cam permitting retractions of the tool-slide and intermittent rotations of the turret at fixed or constant speeds.

35 These cams with all the lobes integral therewith, after being specially shaped for the particular work to be performed, have in practice heretofore been hardened, and the cam once made could not be altered in economical factory practice, and it has heretofore been 40 the practice, if any change in any portion of any one of the lobes was necessary after the cam had been made, to discard the cam entirely and make a new cam, resulting in a new additional expense which is quite material.

45 Not only was it found necessary to provide an entirely new cam with all its lobes, in case any change in cam relation was necessary, due to mistake in layout of any contact portion or to change in product, or other reason, but such cams, when once made with a predetermined relation of speed of rotation of the cam surfaces to the angular distances of the depressions for permitting the intermittent 50 turret rotations, fixed the speed of operation of the machine and the number of pieces which could be made within a stated time, so that if it was found advisable to increase the speed of operation of the machine to produce 55 a greater number of parts for a given interval of time, it was found necessary to make an entirely new cam with all the lobes thereof differently spaced apart for providing different sizes of angular depressions between 60 the lobes in order to permit proper intermit-

tent rotations of the turret without interference between the tools on the turret and the work.

65 In our invention each lobe is a separate part of a composite cam, and we correlate these cam-lobes in angular relation for sequential coaction of the successive cam-lobes with the tool-slide, and space the separate cam-lobes in angular relation for forming depressions between cam-lobes for proper retractions of 70 the end tool-slide permitting turret rotations, and we furthermore provide a coacting part or roller on the actuated lever for effecting 75 tool feeding movements, which coacts with all of the cam-lobes, which are arranged side 80 by side about a common axis.

85 We furthermore provide a series of standard cam-lobes, arranged stepwise in such steps of progression of angular durations and rises as may be determined, so that substantially all usual operations which it may be desired to perform on a machine of this character, are effected by proper selection of such standard cam-lobes and the proper angular placement of such cam-lobes with relation to 90 each other.

95 The circle on which our improved cam-lobes are imposed is divided into one hundred equal angular spaces. Our improved cam-lobes are arranged in steps of angular distances, which may be steps of five hundredths (.05), that is to say, the peripheral cam-faces of the respective cam-lobes, which control 100 duration of tool coaction with the work, occupy angular spaces which differ in steps of five hundredths (.05), one of the cam-lobes having a peripheral cam-face extending throughout an angle of five hundredths (.05), the next throughout an angle of ten hundredths (.10), the next throughout 105 an angle of fifteen hundredths (.15), and so on throughout the series.

110 Our improved cam-lobes are also arranged in steps of rises, which may be steps of twenty-five one-thousandths (.025) of an inch, that is to say, the peripheral cam-faces of the respective cam-lobes, which control distances of tool coaction with the work, rise for distances which differ in steps of twenty-five one-thousandths (.025) of an inch, one 115 of the cam-lobes having a peripheral cam-face which has a rise of twenty-five one-thousandths (.025) of an inch between its lower end and its higher end, the next having such rise of fifty one-thousandths (.050) of an inch, the next having such rise of seventy-five one-thousandths (.075) of an inch, and so on throughout the series. Cam-lobes of 120 various rises are provided for each step of angular distance.

125 The cam-face may at the high end of its rise have a concentric portion or "dwell" face, to cause the tool to dwell at the final portion of its cut for finishing purposes, which dwell face may extend throughout an angle of two 130

one-hundredths (.02) of the circle. This dwell face is exemplified as included in the angular distance or length of the peripheral cam-face of the cam-lobe.

5 Thus we have in Figs. 14, 15 and 16 exemplified three of such cam-lobes.

In the cam-lobe 122 exemplified in Fig. 14, the angular distance occupied by the peripheral cam-face 123 for tool coaction in cutting 10 is five hundredths (.05), represented by the angle a , and the angle of the dwell is two hundredths (.02), represented by the angle b , the angle a for convenience including the angle b . This cam-face has a rise of one hundred and fifty one-thousandths (.150) of 15 an inch, represented at c .

In the cam-lobe 124 exemplified in Fig. 15, the angular extent a of the rise of the cam is thirty-five hundredths (.35), the angle of 20 the dwell b is two hundredths (.02), the angle a being inclusive of the angle b , and the rise c is three hundred and fifty one-thousandths (.350).

In the cam-lobe 125 exemplified in Fig. 16, 25 which is a threading cam, the angular extent of the rise a of the cam is fifteen hundredths (.15), and the angular extent of the fall d of the cam is fifteen hundredths (.15), the inclusive angle of the cam being thirty hundredths (.30). The rise c of this cam is exemplified as three hundred and seventy-five thousandths (.375) of an inch, and corresponds with threading cam No. 7 hereinafter described.

35 Each of the cam-lobes is provided with a quick-rise face 127, at one of its ends, for quickly moving the tool-slide to its proximate position for coaction between its tool and the work, and the cam-lobe is also provided 40 with a quick drop-face 128 at its other end, for permitting the roller to drop quickly off of the cam-face for quick retraction of the tool-slide and tool. The cam-lobes are also provided with a hub 129, which has a rising 45 surface 130 for the roller 57, this rising surface being at the point of extreme retraction of the roller. The hub is not necessarily contacted by the roller when the cam-lobes are assembled as a composite cam.

50 Each of the cam-lobes is provided with a radial line 131 and a radial line 132 to show the angular extent of the rise of the cam, the cam being provided with a mark 133 to denote this angular extent. The lobe may be provided 55 with a further radial line 134, the distance between the radial lines 132 and 134 showing the extent of the dwell of the cam. The latter angle is exemplified as included in the former angle. The cam-lobe may be provided 60 with a mark 135 to denote the angle of this dwell. The line 134 and the mark 135 may be omitted on the assumption that all such cam-lobes are provided with such dwell. The cam-lobe is also provided with a mark 65 136, to denote the extent of rise of the cam.

The respective cam-lobes are formed out of metal plates and have their cam portions suitably hardened after formation. Cam-lobes having thereon cam-faces which cause the respective tools to operate on the work for approximately the durations and for the distances desired upon the work, for performing various operations desired, are selected from the series of standardized cam-lobes, and are angularly arranged about their axes so as to provide depressions 140 between the lobes for reception of the roller 57, to permit retractions of the tool-slide at required intervals for rotations of the turret and presentation of different tools sequentially to the work.

The cam-lobes so selected and angularly arranged about their axes are secured together, so as to form a composite cam, which rotates as a unit about its axis for coaction with the roller 57. The roller is made of such length as to coact with all of the several cam-lobes arranged side by side.

In order to facilitate such arrangement of the cam-lobes, we provide a collar 141 provided with an end annular flange 142. The respective cam-lobes are provided with central holes 143 which snugly fit the collar, so as to center the lobes on the collar. (See Figs. 6, 14, 15 and 16).

The collar is provided with a keyway 144, the radial center of which corresponds to a radial line 145 on the end-face of the collar, which corresponds to the zero position for the angular one hundred spaces about the circumference of the shaft 55. (See also Figs. 12 and 20). This radial line is preferably marked accordingly. This key-slot receives the key 146 between said collar and said shaft. The end face of the collar is provided with a scale 137 of radial lines to correspond with the one hundred spaces of the angular spacings of the cam-lobes. The graduation marks on the end-face of the collar are preferably divided into major groups of ten, which are subdivided into groups of five, which are in turn divided into single hundredths.

The outer periphery of the collar is provided with teeth 138, of which there are one hundred. The tooth-spaces correspond in position with the division lines of the scale 137, and the walls of the holes of the cam-lobes are provided with complementary teeth 139, of which there are also one hundred, the graduations on the end-face of the hub registering with these teeth. This construction enables the accurate assembly of the respective cam-lobes in angular divisions of one-hundredth (.01) on the collar, with accurate placements of the cam-lobes with the desired angular distances between them measured in hundredths.

Fig. 20 represents an assembly of cam-lobes on the collar with the nut of the collar removed, the shaft being shown in the collar

130

and the cam-lobes being imposed on a diagram representing the hundred spaces into which the circle has been divided, as hereinbefore explained.

5 In assembling the cam-lobes on the collar (see Figs. 6, 12 and 20), the first cam-lobe is placed over the collar with its line 131 in line with the zero mark on the scale on the end face of the collar. The next cam-lobe is 10 then slipped over the collar with its angle line 131 in line with that mark of the scale on the end face of the collar as corresponds with the desired position of the cam-face on the second cam-lobe in the composite cam. 15 The third and subsequent cam-lobes are placed over the collar in similar manner to form the composite cam. All of the cam-lobes are clamped to the collar by means of a nut 147 threaded over the threaded end 148 20 of the collar.

The teeth or clutch faces between the walls of the holes in the cam-lobes and the outer periphery of the collar position and maintain the cam-lobes in angular relations so that 25 the cam-lobes have the correct angular positions in the completed composite cam. Six of the cam-lobes are shown mounted on the collar, but if it is desired to use a less number, for instance three, the spaces on the collar which would normally be occupied by cam-lobes may be occupied by filling plates 30 149, (see Fig. 9), which are of the same thickness as the cam-lobes and have an outer periphery corresponding in radial distance to 35 the position of the rising face 130.

The composite cam is, after assembly, placed on the shaft 55, with the key in the collar received in the key-slot in the shaft, (Figs. 12 and 20), to correctly angularly 40 place the composite cam on the shaft. The collar is then clamped to the shaft by means of a nut 150, which is threaded to the threaded end 151 of the shaft. (Fig. 6.) The nut is preferably extended through a bearing 152 in the frame of the machine, and has a polygonal outer end 153 for reception of a wrench. The thread between the nut and the shaft is preferably in such direction that rotation of the shaft in usual direction tends 45 to tighten the nut. There is preferably a space 154 between the end of the shaft and the side frame 155 of the machine so that the composite cam may be conveniently removed from the shaft and passed through an opening 50 156 in the rear of the frame. (Fig. 3.)

The composite cam is rotated by the cam-shaft. The respective cam-lobes coact with the roller 57. The various cam-lobes coact 55 with different parts in the length of the roller in the present exemplification, for causing actuations of the lever 51, and consequent actuations of the tool-slide 22 in cutting directions, the retractions of the tool-slide being 60 automatically obtained and the turret being

automatically caused to turn during retracted positions of the tool-slide.

If it should be found after assembling the composite cam that the speed of cutting may be increased, the angular spaces between the cam-lobes may be increased, as by angularly resetting the various cam-lobes on the collar, or by substituting other cam-lobes having shorter distance angles with the same rises, so as to increase the angular spaces between the cam-lobes in the composite cam in order that proper time may be given between the cutting actuations for turret rotations. 75

If, further, it should be found desirable to change the cam-face on any one of the lobes, 80 a different lobe having the desired cam-face, may be selected from our standard cam-lobes and substituted, and the various cam-lobes reassembled for forming the composite cam, all of the other cam-lobes being retained in the composite cam. Special cam-lobes may also be provided for special or unusual movements of any of the tools, and these may be assembled with our standardized cam-lobes for 85 forming a composite cam. 90

By employment of our invention composite cams may be formed of standardized cam-lobes, and the respective cam-lobes may be employed in any number of composite cams, thus dispensing with the necessity of forming a number of cam-faces on an integral cam, which integral cam can be employed only as an entity for its particular job. 95

In our improved device further the lever 51 for the end-slide and the levers 75, 76, for 100 the cross-slides, are so related in length and position of fulcrum, that the cam-lobes are interchangeable on the end cam-shaft and on the cam-shaft of the cross-slides, so that any of the standardized cam-lobes of our series of cam-lobes may also be employed for operating 105 the cross-slides.

We further provide novel means for angularly relating the cam-lobes for the respective cross-slides, on the cam-shaft for the cross-slides, and with relation to each other. Thus the cam-shaft 103 for the cross-slides is provided with a reduced portion 161, which has a key-groove 162 therein. (See Figs. 1, 10, 11 and 27). A collar 163 is received over this reduced end of the shaft. The respective ends of the collar are provided with reduced ends 164, 165, which respectively have teeth 166 on their outer peripheries, there being one hundred of these teeth on each of these 115 ends, to correspond with the number and arrangement of the teeth in the wall of the hole of the respective cam-lobes. A collar 167 is received over the reduced portion 161 at the inner end of the reduced portion, and has a key-groove 168 therein in line with the key-groove 162. 120

The outer peripheries of the collars 163, 167, are respectively provided with scales 169, 170, the graduations of which are pref- 125 130

erably one hundred in number, to correspond with the one hundred distance spaces of the cam-lobes. (Fig. 10). The marks of these graduations register with the tooth-spaces between the teeth 166, the lines coinciding with the middle of said key-grooves registering with the zero lines of said scales. (Corresponding to the scale showing of Fig. 12). The said scales are preferably divided into major groups of ten, subdivided into groups of five, which are in turn divided into single hundredths.

The side cam-lobes 101, 102, are respectively placed about these reduced ends. Each of the side cam-lobes is placed on its hub with the radial line 131 thereon in registry with that division of the scale which corresponds to the desired position of the beginning of the rise of the cam-lobe on the cam-shaft 103. (See Figs. 21, 22, 27 and 28). A key 171 is located in the key-grooves 162, 168, and in a complementary key groove in the shaft extension, so as to angularly position the collars 163, 167, on the cam-shaft 103. (Fig. 10.) The positioning of each side cam-lobe with its graduation mark 131 in registry with the desired one of the marks of the respective scales 169, 170, angularly positions the cam-lobes for the cross-slides on the cam-shaft 103 and with relation to each other. The position of the cam-lobes on the cam-shaft and with relation to each other can therefore be accomplished in steps of one hundredths.

Each of the side cam-lobes is thereby placed in such angular relation on the cam-shaft 103 that the beginning of the rise of each of these cam-lobes is in correct position for the work to be performed by the cross-slide. The collars and cam-lobes are placed in this assembled relation on the shaft extension 161.

Each of the cam-lobes may also be moved endwise off of its collar, rotated and replaced on its collar to change its angular relation with the cam-shaft 103 and with relation to the other of said cam-lobes, while the collars are on the cam-shaft.

A clutch collar 172 is received over the shaft extension and is rotatively held thereto by means of the key 171. A nut 173 is received within the clutch collar and over the threaded end of the shaft extension, and clamps all of the collars and the side cam-lobes rigidly to the shaft. The complementary clutch-member 174 is movable endwise into engagement with the clutch-collar 172 when desired. (Figs. 1, 10 and 11).

Exemplifying the operation of our invention, Fig. 17 represents a table of operations for forming the piece of work 175 shown in Fig. 19. Column 177 is a column of operations to be performed. Column 178 is a column designating the tool feed per revolution calculated for each of the end tools. Column 179 is a column of number of revolutions calculated for each of the operations. Column

180 shows the angular distances in hundredths or angular durations of the cam-lobes calculated for the various operations including the dwell faces on the various cam-lobes, this column also including the angular spaces in hundredths for turret operations. Column 181 enumerates the depths of cut for the various tool operations of the end tools, designated in thousandths of an inch. Column 182 designates the depths of cut and calculated angular distances for the tool operations of the side tools, the designations being bracketed about those end cutting operations during which the operations of the side-tools take place.

Assuming now that it requires 27 revolutions of the spindle to index the turret, as per calculation in column 179, and that it is desired to index the turret in an angular movement of the composite cam of .05, each angular movement of .01 will equal 5.4 revolutions of the spindle, making a total of 540 revolutions of the spindle for one complete rotation of the composite cam, the proper speed change being made in the change gears 110 to produce this result. It will be assumed further that cam-lobes in steps of angular distance of .05 only are available.

In selecting the proper cam-lobes in steps of .05 for the various tools, and greater numbers of revolutions being allowed for the cutting operations, such cam-lobes are selected as most closely approach the calculated angles set forth in column 180 which are of the next greater value to those given in such column. Thus a cam-lobe of .15 angle is selected for the box tool and dwell, which cam-lobe acts in the tool-cutting function during the number of revolutions of the spindle that 15 multiplied by 5.4 equals, namely 81 revolutions, being the number of revolutions designated in column 185.

In this tabulation, column 184 represents the resultant selected tool feeds per revolution; column 185 is a column of the number of revolutions of each of the operations during the angular movements of the cam-lobes selected, the selected angles of cam-lobes being found in column 186, which also includes the selected angles for feeding the stock and for turret indexings. The rise in thousandths of the cam-lobes in column 187 for each operation remains the same as the depth of cut designated in column 181, threading cam No. 4 hereinafter described being selected for producing the required depth of threading cut. Column 188 designates the cam-lobes selected for the side tools, the upper one of these cam lobes being the forming cam-lobe and having a rise of .150 inch and an angle of .45, and being bracketed about the .45 angle during which the center drill to the drill .625 inch deep inclusive operate. The lower side cam-lobe is for the cutting-off operation and has an angle of .10, coincident with the last tur-

ret indexing and dwell in the column 177 of operations to be performed.

Corresponding designations of operations of the end-slide are imposed on Fig. 20, which 5 shows a face view of the selected standard cam-lobes and the relative positions of the same for forming the composite cam assembled to perform the various operations necessary to complete the piece of work shown 10 in Fig. 19, by selection of cam-lobes from a set of cam-lobes, the angular distances of durations of whose cam-faces 123 are divided into steps of five hundredths (.05) and whose rises are divided into steps of twenty-five 15 thousandths (.025) of an inch.

These cam-lobes are quickly assembled by selection from the series of standard cam-lobes and quickly placed upon the machine, and production of the repetitional work is 20 quickly begun without the necessity of first forming an integral cam having thereon all of the cam surfaces necessary to form that particular piece of work, as has been the usual practice heretofore, with the chance, 25 further, in the usual practice heretofore, if a mistake be made in any portion of the integral cam, that a new integral cam would have to be made, all at additional expense, which expense is prohibitive for the production 30 of work of this character in comparatively small numbers, but which work is economically and quickly performed by employment of our invention.

As an example, it may be stated that by 35 providing our improved series of cam-lobes only in steps of five hundredths (.05) of angular differences, and in steps of rises having differences of twenty-five one-thousandths (.025) of an inch, all of the usual combinations 40 of angular distances or durations and rises or extents of movements of the tool may be provided for usual operations.

In the example stated, and referring to Figs. 13, 17 and 20, the bar to be cut is fed 45 endwise in the hollow spindle against the stock-stop 191 in the turret, and clamped, the roller 57 coacting with the cam-lobe 192 shown in Fig. 20. The cam-lobe for stopping the stock has a contact-face which has no 50 rise and extends throughout the desired angle.

The turret is then automatically retracted and automatically indexed, that is, rotated one-sixth of a revolution during retracted 55 position of the turret for presenting the box-tool 193 to the work.

This box-tool cuts the annular rabbet 194 on the piece of work, exemplified of brass, the roller 57 coacting with the cam-lobe 195 60 shown in Fig. 20. The box-tool is retracted, and the turret again indexed for bringing the next tool 196, which is a center drilling tool, in line with the work.

This center drilling tool drills a small centering hole 190 in the end 197 of the work,

the roller 57 coacting with the cam-lobe 198 shown in Fig. 20. The turret is next indexed for causing registry of the drill 199 on the turret with the work.

The turret is next caused to approach the work under coaction of the roller 57 with the cam-lobe 200 shown in Fig. 20, for drilling the hole 201 in the end of the work to a depth of three-eighths ($\frac{3}{8}$) inch by employment of the drilling tool 199, this tool entering the centering hole previously made. The drilling tool is withdrawn, the turret being indexed for presenting the next drilling tool 202 to the work, the tool entering the hole 201, the roller 57 coacting with the cam-lobe 203 shown in Fig. 20, for drilling the hole 205 to its depth of five-eighths ($\frac{5}{8}$) inch.

Upon withdrawal of the last-named tool, the turret is again indexed for presenting the tapping tool 204 to the work for the purpose 85 of threading the hole 201 just formed.

The forming tool 47 on the front cross-slide 41, for forming the annular rabbets 211, 212, on the piece of work, is moved into the work by the cam-lobe 101, (see Fig. 21), which 90 moves the front cross-slide 41, the front cross-slide then being retracted. This operation takes place during the time that the cam-lobe 198 acts on the end-slide for the center drilling operation, the next indexing of the turret, the following coaction of the cam-lobe 200 with the end-slide for the initial drilling, the following turret indexing, and the coaction of the next cam-lobe 203 with the end-slide for completion of the drilling.

The tapping tool 204 on the end slide has just been presented to the work, as hereinbefore stated. The work is assumed to rotate at a speed of 4800 R. P. M. This speed being too high for successful tapping, rotation is imparted to the tapping tool in the same direction as the direction of rotation of the work, by means of the bevel gears 213, 214, (Fig. 13), operated in usual manner, for rotating the tapping tool at one-half the speed of rotation of the work, namely, at 2400 R. P. M. The tapping tool advances into the work under influence of coaction of the roller 57 with the cam-lobe 215 shown in Fig. 20. The rotation of the work is then stopped, that of the tapping tool, however, continuing, with the result that the tapping tool follows the threads just made in the piece of work, while the tapping tool is being withdrawn.

In this connection it may be stated that it is preferable to employ a tapping tool which is floatingly mounted, for instance as exemplified in Fig. 13. This tapping tool comprises a hollow shank 219 provided with a flange 221. The shank is inserted in a bushing 220 fixed in the turret and rotates in this bushing. It is axially held in the bushing by the flange 221 at its outer end, the inner end thereof having the bevel-gear 214 fixed

70

75

80

100

105

110

115

120

125

130

thereto. A chuck 222 has the tap 204 fixed therein, the tap being inserted the desired depth to produce the desired taping cut. The chuck is provided with a stem 224 reciprocating endwise in the bore of the shank 219. Guide-pins 225 are fixed to the chuck and slide endwise in holes 226 in the hollow shank 219, for rotatively holding the chuck to the hollow shank and permitting endwise movement of the chuck, so that, after the tap has entered the bored hole in the work and begun its threading, the movement of the tool is primarily controlled by the threading. For normally retracting the tapping chuck, the stem 224 has a spring 227 received thereabout, the spring being located in an enlargement 228 in the bore of the hollow shank 219. A nut 229 is threaded over the threaded end of the stem. The spring is located between said nut and the shoulder at the inner end of the enlargement for urging the tapping tool inwardly. When the tapping tool has been withdrawn, rotation of the work again begins, accomplished in usual manner.

The advancing of the tap is caused by coaction of the rise cam-face 230 of the cam-lobe 215, with the roller 57, during the threading operation, and the tap is withdrawn for the unthreading operation during coaction of the roller 57 with the fall cam-face 231 on the cam-lobe 215.

The turret is next indexed, and the end-slide is then advanced for again placing the stock-stop 191 in line with the stock to be fed.

During the last-named indexing of the turret and prior to beginning of the next feeding movement of the stock, the rear cross-slide is advanced toward the work by means of the side cam-lobe 102, (see Fig. 22), and withdrawn out of range of the stock, the rear cross-slide being provided with the cutting-off tool 48.

The finished piece of work drops, and the next feeding movement is imparted to the bar of stock from which the pieces are being cut immediately after retraction of the side cutting-off tool 48 a sufficient distance to clear the stock. The end of the bar of stock is fed against the stock-stop 191, which, as just explained, has by the last indexing of the turret been again presented to the end of the stock, ready for repetition of the series of operations.

In the example stated, referring to Figs. 20, 21 and 22 and columns 186 and 188 of Fig. 17, it will be noted that cam-lobes only are employed of the series having differences in angular distances of five-hundredths (.05), and it will be noted from the memorandum made at the foot of columns 184 to 188 inclusive, that the time consumed for forming each piece is 6.75 seconds. At this speed each indexing of the turret takes place dur-

ing an angular movement of the composite cam of .05.

It may be desired, however, as hereinbefore explained, to decrease the time in which to form each of the pieces, and to approximate more closely to the calculated data contained in columns 178 to 182 inclusive. Assuming, therefore, that it is desired to form each of the pieces in 5 seconds, made possible by softness of stock being used or for other reason, and assuming further that cam-lobes having differences in angular distances of .05 only are available, the number of hundredths of angles required for indexing the turret contained in column 180 are taken as a basis, and the spindle having a speed of 4800 R. P. M., the spindle speed in 5 seconds would be 400. Each hundredth angle therefore represents 4 revolutions and multiplying the 7 by 4 gives the result of 28 revolutions required for indexing the turret. It will be noted that the cam-lobes are so mounted that the angular distances between cam-lobes are divided into steps of .01 angles.

Cam-lobes in steps of .05 angles only being available, such cam-lobes are selected for the various cutting operations as most closely approach the calculated angles contained in column 180, using cam-lobes having steeper peripheral cam-faces where lighter cuts are being taken and compensating that with cam-lobes having peripheral cam-faces not so steep where heavier cuts are being taken, and dividing the angles available among the various cutting operations accordingly. The selected tool feeds per revolution given in column 232 are the results of the selections of the angles and rises.

Selected tool-feeds per revolution, selected numbers of revolutions, selected angular distances, selected rises in thousandths, and data as to side cam-lobes, as designated in the respective columns 232, 233, 234, 235 and 236, thus selected produce the desired result.

By the selection of cam-lobes arranged in differences of five-hundredths (.05) and designated in columns 234, 236, and providing an angular travel of seven-hundredths (.07) for turret indexing, a composite cam is assembled such as shown in Fig. 23, in which the cam-lobes are designated respectively by the numerals 192, 242, 198, 200, 245 and 246. In this instance threading cam No. 2 hereinafter described is employed. This composite cam, similar to the composite cam shown in Fig. 20, is imposed on an angular scale showing the hundred divisions of the circle. The operations corresponding to the operations in column 177 are also imposed on this figure.

The side cam-lobe 101 for the front cross-slide 41 for side forming the work, shown in Fig. 21, and the side cam-lobe 102 shown in Fig. 22, for the rear cross-slide 42 having the cutting-off tool thereon, similarly arranged and timed as in the last preceding instance,

are employed in connection with the composite end-cam shown in Fig. 23.

In this instance, in order to save angular distance for operations, the angular distance of the dwelling face of the cam-lobe for stock-feed, which should be of the same angular distance as the angular distance reserved for turret operation, which, at the speed of finishing each piece of work instanced, is .07, is reduced to .05, but the .07 is allowed, beginning with the zero mark on the scale on the end of the collar. This is permissible because the stock-bar fed by the stock feeding means will not have reached the dwell-face of the cam 192 for stock-stop, until the initial angular movement of .02 will have been made, so that the end of the stock will properly engage the stock-stop.

The time, five seconds, for forming each piece of work, is noted at the bottoms of columns 232 to 236 inclusive.

The steps of differences in angular distances of the cam-lobes may be still further sub-divided, for instance, by sub-dividing the steps of angular distances of the cam-lobes into single one-hundredths.

Assuming now that the same piece of work is to be formed by employment of the set of cam-lobes with such more minute sub-divisions of one-hundredths, and that it should be desired to finish each piece of work in five seconds, each piece of work is formed during 400 revolutions of the spindle and each indexing of the turret is performed during an angular movement of the composite cam of .07, equaling 28 revolutions of the spindle. The angular distances are the same in this instance as the angular distances in the calculation found in column 180. The selected tool-feed per revolution, selected number of revolutions, selected angular distance in hundredths, rise in thousandths, and data as to side cam-lobes, as designated in the respective columns 252, 253, 254, 255, 256, will produce the desired result. Threading cam No. 2 hereinafter described is selected for the threading operation. By selection of cam-lobes having the angular distances designated in column 254 and the rises designated in column 255, a composite cam is assembled as shown in Fig. 26, this composite cam being imposed on an angular scale of one hundred divisions in the circle, and this figure having the operations of column 177 imposed thereon. The cam-lobes in this figure are designated by the reference numerals 261, 262, 263, 264, 203 and 246.

A side cam-lobe 267, shown in Fig. 27, for operating the front cross-slide, similarly placed as in preceding instances, is employed in connection with the composite cam shown in Fig. 26. A side cam-lobe 268, shown in Fig. 28, is employed in the last instance for operating the rear tool-slide having the cut-off tool mounted thereon.

These examples illustrate the adaptability of our invention to various conditions and exemplify its extreme flexibility.

A table of standardized cam-lobes is shown in Fig. 29, in which the cams are indicated as divided into steps of angles of five hundredths (.05) in bolder numerals and as sub-divided into angular distances of one-hundredths (.01) in lighter numerals.

The cam-lobes of various angular distances are divided into steps of rises of twenty-five thousandths (.025) of an inch. The minor subdivisions of angular differences of one-hundredth (.01) may be continuous throughout the series or such portions of the series as may be desired. We have omitted portions of the enumerations in Fig. 29 on account of lack of space. It is also to be understood that the provisions of cam-lobes having series of steps of angular distances and steps of rises may be extended beyond that shown in the tabulation.

When forming stock of greater diameters, with cutting operations of greater depths, than come within the range of the tabulation in Fig. 29, cam-lobes will be employed having greater angular distances and greater rises than tabulated in this figure, the tabulation being merely extended however to cover a wider range of cam-lobes, and the cam-faces on the cam-lobes may be at greater distances from their axes of rotations dependent on the size of machine employed.

The tabulation shows a column of angular distances, a cross line of designated rises, and columns of such designated rises complementary to the various angular distances noted. The tabulation is divided into spaces 271 at the crossing points of the cross-lines of angular distances and vertical columns of rises, to designate the desired cam-lobes provided. The spaces designating sizes not needed are concealed by cross-marks 272 therein.

Thus spaces in the lower left hand part and the upper right hand part of the tabulation are so cross-marked. Cam-lobes of certain angular distances may also extend throughout only a given series of rises and cam-lobes of certain rises may extend throughout only a given series of angular distances.

The tabulation shows the cam-lobes which the user of the machine has on hand and the user will select the cam-lobe on hand which appropriates most nearly the cam-face which his calculation shows to be the proper cam-face, dependent on the character of work. If the user desires to use a cam-lobe having a rise of one hundred and fifty thousandths (.150) of an inch and an angular distance of twenty hundredths (.20), usually expressed 150/20, he can readily see, by referring to the vertical column, "Angular distances" in the tabulation shown in Fig. 29, that he has a line of cam-lobes of the desired angular distance, and by reference to

the horizontal line of headings of rises that he has a column of cam-lobes of rises of one hundred and fifty thousandths (.150). The space at the crossing point between such line and column shows the presence of the cam-
lobe 150/20 desired. Then all he needs to do is to select such cam-lobe so designated and make it a part of the composite cam.

Reference numerals the same as those designating the cam-lobes in the exemplifying composite cams shown in Figs. 20, 23 and 26, and the side cam-lobes shown in Figs. 21, 22, 27 and 28, are shown in the corresponding spaces in the tabulation of Fig. 29, to show which of the cam-lobes enumerated in said tabulation are used in forming said composite cams and as side cam-lobes.

We have in Fig. 25 shown a tabulation of threading cam-lobes, it being assumed that the cam faces for the rise and the fall on the cam-lobe are of equal extents. The number of threading cam-lobes required for a given series of our standardized cam-lobes is small. The provision of threading cam-lobes may also be extended for machines of greater or different capacities.

In this tabulation there are vertical columns having headings of angular distances divided into steps of five-hundredths (.05). These angular distances are inclusive of the rise and the fall of the threading cam-lobe, that is, of the threading and the unthreading operations. Each of these columns includes steps of rises. There is a column of cam-lobe numbers, the numbers of which are respectively in line with the respective designations of rises in said columns. The spaces at the crossing points between cross lines of cam-lobe numbers and columns of angular distance have the rises of the cam-lobes designated therein. The rise of each cam-lobe increases with the increase of its angular distance.

This tabulation provides for threading cam-lobes for a range of desirable angular distances and rises ordinarily employed within the range of cam-lobes designated in the tabulation of Fig. 29. The tabulation of threading cam-lobes, and the corresponding threading cam-lobes, may, however, be extended or subdivided both with relation to angular distances and rises.

We have also in Fig. 24 shown threading cam-lobes of the given numbers shown in Fig. 25, and having the angular distances and rises designated in the tabulation of threading cam-lobes shown in Fig. 24, the representations of these threading cam-lobes being imposed one on the other and shown imposed on a circle. The respective cam-lobes are designated by cam numbers corresponding to the numbers in the tabulation in Fig. 25. The threading cam-lobes have rise cam-faces 230 and fall cam-faces 231,

as well as quick-rise faces 273 and quick-drop faces 274.

Further illustrating the proper selection of threading cam-lobes, threading cam-lobe No. 3 has a rise of .158 for an inclusive angle 70 of .05; a rise of .316 for an inclusive angle of 10; a rise of .474 for an inclusive angle of .15; and a rise of .625 for an inclusive angle of .20. The inclusive angles are determined by the points of contact of the roller 47 with the cam-lobe for the beginning of the rise and end of the retraction of the threading tool in the threading operation.

From this explanation the application of the tabulation of threading cams shown in Fig. 25 to the threading cam-lobes shown in Fig. 24 may be readily perceived.

It may be here stated that a threading tool which has the beginning of its threading connection made with the work will follow 85 through with its threading operation, controlled by the threading rather than by the form of the apex portion of the threading cam, especially when a yieldable threading chuck such as shown in Fig. 13 is employed, 90 providing extreme flexibility in selection of the proper threading cam.

To find the proper threading cam, take the number of hundredths of the inclusive angle and the length of thread or rise in 95 thousandths shown by the calculation for the threading cam, and select the nearest cam.

The calculation shows, for instance, that in order to cut a quarter inch thread having twenty-four threads to the inch and cutting 100 this thread one-fourth inch long, it requires an inclusive angular distance of .06 and a rise of .250. The table of threading cams shows that cam No. 2 has a rise of .203 in .05, which is sufficiently near for all practical purposes. This threading cam-lobe has been selected for the composite cams shown in Figs. 23 and 26.

If the calculation shows that a threading cam is needed which has a rise of .250 of an 110 inch in an inclusive angular distance of .10, reference to the tabulation of threading cams shows that cam-lobe No. 4 is the cam-lobe desired. This is the cam-lobe employed in the composite cam shown in Fig. 20.

The quick rise portion and the quick drop portion of the cam-lobes thus far described are preferably arranged for highest speed of rotation of the composite cams. Additional 120 series of cam-lobes, extending partially or wholly throughout the series of cam-lobes hereinbefore described, but provided with different slopes of quick rise faces and quick drop faces, may be employed for marked decreases in speeds of rotation of the composite 125 cams, so as to provide more abrupt movements of the roller 57 coacting with the composite cam toward and from the axis of said cam during movements of the tools into cutting positions and into retracted positions. 130

Thus in Figs. 14 and 15 the dotted lines 276, 277, represent such additional quick-rise faces and 278, 279, represent such additional quick-drop faces of such cam-lobes. These 5 additional quick-rise faces and quick-drop faces are provided in instances where it is desired to more quickly move the tools into and out of operative positions relatively to the speed of rotation of the composite cam, 10 that is, in a shorter angular distance, for advancing the relative times of indexings of the turret.

The respective cam-lobes are provided with a mark 281 to denote the lead of the 15 quick-rise edge thereof and with a mark 282 to denote the lead of the quick-drop edge thereof, the slopes of such edges being tabulated respectively as 1, 2 and 3.

Such further elaboration in supplying 20 cam-lobes is, however, presented for ultimate refinement in sub-divisions of cam-lobes in employing our invention.

Our improved standardized cam-lobes, 25 corresponding to the series of standardized cam-lobes disclosed by and as explained with reference to the tabulation of Fig. 29 and the threading cams in Figs. 24 and 25, provide cam-lobes for substantially all operations throughout the range given, and may be selectively assembled in desired relations, and 30 immediately used on the machine, resulting in great economy of manufacture, and avoiding the necessity of forming integral cams having various and succeeding cam portions 35 for each piece of work manufactured.

For ordinary and usual operations, the provision of cam-lobes of the series of bold face numerals in Fig. 29, is sufficient for the range of work included in said tabulation. 40 There is, however, greater economy in supplying all of the cam-lobes of ultimate refinement and employing these cam-lobes in assembling composite cams under the teachings of our invention by far than in the formation of an integral cam with all the cam-faces thereon for each particular job or piece 45 of work which is to be formed in a factory doing a diversified character of work of this nature.

Our invention provides extreme flexibility 50 in the selection and assembly of cam-lobes for forming composite cams, and for selective employment in end cams and for side cams; provides economy and saving of time 55 in producing repetitional work of the character mentioned, and is especially important under the conditions of manufacture prevailing and threatening to continue under which repetitional work is ordered only in comparatively 60 small quantities, and under which reproducing of repetitional work in large numbers is being discontinued.

Having thus fully described our invention, 65 what we claim as new, and desire to secure 70 by Letters Patent, is:

1. In combination, with a tool-turret and an actuating part therefor, of separate cam-lobes having peripheral active cam-faces arranged in steps of angular distances and in steps of rises about and in relation to a common axis and extending in planes substantially perpendicular to said axis, a part arranged about said common axis, said last-named part and said respective cam-lobes having graduations and complementary indicating means angularly positioned with relation to said peripheral active cam-faces for angularly setting said cam-faces about said axis and for selectivity in assembling separate cam-lobes for forming a composite cam 80 with angular depressions between said lobes, for coaction with said actuating part in performing cutting operations and permitting rotations of said tool-turret between cutting operations in an automatic forming machine. 85

2. In combination, with a turret tool-slide and an actuating part therefor, of separate cam-lobes having peripheral active cam-faces arranged in steps of angular distances and in steps of rises about and in relation to a common axis and extending in planes substantially perpendicular to said axis, a part arranged about said axis, said separate cam-lobes and said last-named part forming relative angularly positioned members one of 90 which is provided with indicating means and the other of which is provided with graduations forming complementary elements one of which can be angularly set with relation to each other for interchangeably positioning said cam-lobes in said angular relation about said common axis for forming a composite cam having selected separated cam-lobes and cam-faces arranged in cam-relation to said common axis and with relation to each other about the axis of said composite cam, and respectively provided with a quick rise edge and with a drop edge, and said edges of proximate cam-lobes spaced angularly from each other for forming angular depressions between said cam-lobes radial with relation to said axis, for coaction with said actuating part in an automatic forming machine for cutting movements and retracting movements of said turret tool-slide, and means for 100 guiding said turret tool-slide in directions at right angles to said last-named axis. 105

3. In an automatic forming machine, the combination of a series of separable cam-lobes having peripheral cam-faces arranged in steps of angular distances and in steps of rises in relation to a common axis of rotation of said cam-lobes, said cam-lobes extending in planes substantially perpendicular to said axis, a part arranged about said axis, said respective cam-lobes and said last-named part forming relative angularly positioned members one of which is provided with indicating means and the other of which is provided with graduations forming com- 115 120 125 130

plemental elements one of which can be angularly set with relation to the other for positioning said cam-lobes with their respective peripheral cam-faces in said angular relations about said common axis, said cam-lobes arranged side by side and in angular relation to each other in said machine for forming angular recesses between cam-lobes radial with relation to said axis, a tool-slide, 5 means for guiding said tool-slide in directions at right angles to said axis, and operating means for said tool-slide comprising an operating part having coaction with all of said cam-lobes so arranged side by side and received in said angular recesses.

4. A series of cam-lobes for employment in an automatic forming machine of the character described, said cam-lobes provided with peripheral cam-faces arranged in steps of angular distances and in steps of rises about 20 a common axis, a part about said common axis having graduations thereon, said cam-lobes having indicating marks thereon, said cam-lobes arranged to be selectively placed 25 and angularly arranged about said common axis with spaces therebetween radial with relation to said axis by registry of said indicating marks with selective ones of said graduations, for forming a composite cam for 30 action with an operating part for a turret-slide and turret in an automatic forming machine, for reciprocating said turret-slide during coaction with said cam-faces and for rotations of said turret during locations of said 35 operating part in said spaces.

5. Series of cam-lobes for employment in an automatic forming machine of the character described respectively having peripheral active cam-faces arranged in relation to a 40 common axis of rotation in steps of angular distances and in steps of rises about and in peripheral cam-relation to said common axis, said cam-lobes provided with indicating marks angularly related to said respective peripheral active cam-faces, and a support for 45 said cam-lobes having graduations thereon with respect to which the marks on said cam-lobes can be angularly set, for providing standardized cam-lobes which are arranged 50 to be selectively placed side by side and angularly arranged about said common axis for coaction in an automatic forming machine.

6. In combination, a cam-shaft, a collar, a series of cam-lobes arranged in steps of angular 55 distances and in steps of rises about and in relation to a common axis and extending in planes at substantial right angles to said axis, said cam-lobes having peripheral active cam-faces and respectively provided 60 with indicating marks in angular relation to said respective cam-faces, said collar having graduations thereon with respect to which said marks of said cam-lobes can be angularly set, and providing standardized cam-lobes 65 which are arranged to be selectively placed

and angularly arranged side by side upon said collar about the axis of said collar with the cam-faces of said cam-lobes extending in peripheral cam-relation to said axis, and means for securing said collar and said cam-lobes together in selected angularly spaced 70 relation for forming a selective cam-assembly, and angular positioning means between said cam-shaft and said collar.

7. In an automatic forming machine of 75 the character described, the combination of a series of cam-lobes arranged in steps of angular distances and in steps of rises about and in peripheral cam-relation to a common axis for selectivity in assembling selective 80 ones of said cam-lobes side by side and in angular relation to each other and with angular spaces between each other in said machine, said cam-lobes having peripheral active cam-faces, a part about said common 85 axis, said last-named part and said respective cam-lobes provided with graduations and complementary indicating means angularly positioned with relation to said peripheral active cam-faces for angularly 90 setting said cam-faces about said axis, a tool-slide, a tool-turret thereon, means for guiding said tool-slide for movement of said tool-slide at right angles to said axis, operating means for movement of said tool-slide comprising an operating part having coaction 95 with cam-faces of said assembled selected cam-lobes for moving said operating part in a plane substantially perpendicular to said common axis, and operating means for intermittently rotating said tool-turret during location of said operating part in said angular spaces.

8. In an automatic forming machine of 100 the character described, the combination of an end-slide, a cross-slide, a lever for each of said slides, said levers having operative ends for reciprocating said respective slides, a cam-shaft for said end-slide, a cam-shaft for said cross-slide, cam-lobes having cam-faces in cam relation to their axes of rotation, and means for interchangeably placing said cam-lobes on said respective cam-shafts, said respective levers having operating parts thereon coacting with said cam-lobes, and the fulcrums of said respective levers so positioned with relation to their 105 said operative ends and their said operating parts as to permit interchangeability of the same cam-lobes on said respective cam-shafts 110 for correlated operative effects upon both said slides.

9. In an automatic forming machine, the combination of a turret-slide, a tool-turret thereon, a lever for moving said turret-slide in cutting direction, a plurality of separable cam-lobes arranged side by side, means for adjustably fixing said cam-lobes on a common axis in angular relation to each other 115 and forming angular recesses between prox- 120 imity.

- mate angularly positioned cam-lobes, said cam-lobes having cam-faces in cam relation to their axes of rotation said last-named means including a part about said common axis, said respective cam-lobes and said last-named part respectively provided with graduations and indicating means complementary thereto, and means mounting said cam-lobes and said lever on substantially parallel axes in said machine, for coaction with said lever, said lever provided with a coacting part arranged to be received in said recesses, and said respective cam-lobes coacting with said coacting part between movements of said coacting part into said respective recesses.
10. In an automatic forming machine, the combination of a turret-slide, a tool-turret thereon, a lever for moving said turret-slide in cutting direction, a series of separable cam-lobes arranged in steps of angular distances and in steps of rises side by side about and in cam relation to a common axis and extending in planes substantially perpendicular to said common axis for selectivity in assembling selective ones of said cam-lobes in angular relation to each other with angular spaces between each other and forming a composite cam having peripheral cam-faces and peripheral recesses between angularly adjacent cam-lobes said last-named means including a part about said common axis, said respective cam-lobes and said last-named part respectively provided with graduations and indicating means complementary thereto, means for rotating said composite cam, said lever provided with a contact-part coacting with said respective cam-lobes and received in said peripheral recesses, means for automatically retracting said turret-slide and for reception of said contact-part in said peripheral recesses, and means for automatically rotating said tool-turret during such retracted positions of said turret-slide.
11. In an automatic forming machine, the combination of a turret-slide, a tool-turret mounted thereon, a lever for moving said turret-slide, a series of separable cam-lobes arranged in steps of angular distances and in steps of rises side by side about and in cam relation to a common axis and extending in planes substantially perpendicular to said common axis for selectivity in assembling, a part about said axis, selective ones of said cam-lobes arranged in angular relation to each other with angular spaces between each other as a composite cam having peripheral cam-faces and peripheral recesses between angularly adjacent cam-lobes, said last-named part and said cam-lobes respectively provided with graduations and indicating means complementary thereto for angularly relating said cam-lobes, means for mounting said composite cam in said machine, and means for rotating said composite cam for coaction with said lever whereby to move said turret-slide in cutting directions.
12. In an automatic forming machine, the combination of a tool-slide, an actuating part therefor for moving said tool-slide in cutting direction, means for retracting said tool-slide, a cam-shaft, a series of separable cam-lobes arranged in steps of angular distances and in steps of rises side by side about and in cam relation to a common axis and extending in planes perpendicular to said common axis for selectivity in assembling, a plurality of said cam-lobes arranged selectively about said shaft with the cam-faces of said cam-lobes in cam relation to the axis of rotation of said shaft, and means for adjustably fixing the angular relations between said cam-lobes for forming peripheral depressions adjustable for angular distance between said cam-lobes, said last-named means including a part about said common axis, said respective cam-lobes and said last-named part respectively provided with graduations and indicating means complementary thereto, and said actuating part provided with a coacting part for said cam-lobes arranged to be received in said depressions during retractions of said tool-slide.
13. In an automatic forming machine, the combination of a series of separable cam-lobes having peripheral active cam-faces and a collar, said respective cam-lobes provided with holes, the walls of said holes and the outer periphery of said collar provided with complementary positioning parts angularly divided and angularly related to said active peripheral cam-faces, said collar and said respective cam-lobes respectively provided with angular graduations and a positioning mark complementary thereto angularly related to said active peripheral cam-faces and said positioning parts, whereby all of said cam-lobes are individually adjustably angularly positioned about said outer periphery of said collar independently of each other.
14. In an automatic forming machine, the combination of a series of separable cam-lobes having peripheral active cam-faces and a collar, said respective cam-lobes provided with holes, the inner peripheries of the walls of said holes and the outer periphery of said collar provided with complementary positioning parts angularly divided into hundredths, and said cam-lobes and said collar provided with complementary angular graduations and positioning means complementary thereto angularly related to said active peripheral cam-faces and said complementary positioning parts for angularly relating said cam-lobes and said collar, whereby all of said cam-lobes are individually angularly positioned independently of each other about said outer periphery of said collar.

15. In combination, cam-lobes arranged in steps of angular distances and in steps of rises and threading cam-lobes arranged in steps of angular distances and rises about and in cam relation to a common axis and having peripheral recesses between angularly adjacent cam-lobes, said respective cam-lobes and threading cam-lobes all being separable from each other and extending in planes substantially perpendicular to said common axis, a part about said common axis, said part and said cam-lobes respectively provided with graduations and indicating means complementary thereto for angularly relating said cam-lobes about said common axis, and arranged for selective assembly as a composite cam having peripheral cam-faces and peripheral recesses between all angularly neighboring cam-faces for the purpose described.
16. In a machine of the character described comprising an endwise movable turret-slide and turret for operating endwise on the work, and means for intermittently rotating the turret, the provision of separable cam-lobes arranged in steps of angular distances and in steps of rises for selectivity in assembling separable cam-lobes about a common axis perpendicular to the endwise movement of said endwise movable turret-slide with the cam-faces of said cam-lobes arranged in peripheral cam-relation to said axis, with recesses therebetween, a part arranged about said common axis, said part and said separable cam-lobes respectively provided with graduations and complementary indicating means arranged to be relatively angularly positioned for angularly setting the active peripheral cam-faces of said cam-lobes for forming a composite cam for action of said separate cam-lobes with said endwise movable turret-slide for operating endwise on the work, and said recesses permitting retractions of said turret-slide for intermittent rotative movements of said turret.
17. In an automatic forming machine of the character described, the combination of work feeding and holding means, a slide, means for guiding said slide parallel with the axis of said work holding means, a tool-turret on said slide, a cam-shaft at substantial right angles to said axis of said work holding means, separable cam-lobes having peripheral active cam-faces for moving said slide lengthwise of said axis of said work holding means, a part about the axes of said cam-lobes, said last-named part and said respective cam-lobes having graduations and complementary indicating means angularly positioned with relation to said peripheral active cam-faces of said cam-lobes and arranged for selectively angularly positioning said cam-lobes side by side about the axis of said cam-shaft with angular spaces therebetween, an operated part having operative connection with said slide coacting with said cam-lobes for moving said slide lengthwise of said axis of said work holding means, and means operating to intermittently rotate said tool-turret during complementary relations of said operated part in said angular spaces.
18. In an automatic forming machine of the character described, the combination of work feeding and holding means, a slide, means for guiding said slide parallel with the axis of said work holding means, a tool-turret on said slide, a cam-shaft at substantially right angles to said axis of said work holding means, and separable cam-lobes having peripheral active cam-faces for moving said slide lengthwise of said axis of said work holding means, a part about the axes of said cam-lobes, said last-named part and said respective cam-lobes having graduations and complementary indicating means angularly positioned with relation to said peripheral active cam-faces of said cam-lobes and arranged for selectively angularly positioning said cam-lobes side by side about the axis of said cam-shaft with angular spaces therebetween, an operated part having operative connection with said slide coacting with said cam-lobes for intermittently moving said slide lengthwise of said axis of said work holding means, and means operating to intermittently rotate said tool-turret during complementary relations of said operated part in said angular spaces, and said means for adjusting the angular relation between cam-lobes permitting changing the angular sizes of said angular spaces for permitting changing the speeds of intermittent movements of said tool-slide, the durations of said intermittent rotations of said tool-turret being fixed.
19. In an automatic forming machine of the character described, the combination of work feeding and holding means, a slide, means for guiding said slide parallel with the axis of said work holding means, a tool-turret on said slide, means for intermittently rotating said tool-turret, a cam-shaft at substantial right angles to said axis of said work holding means, the speed of intermittent rotations of said tool-turret being constant, means for changing the speed of said cam-shaft, separate cam-lobes having peripheral active cam-faces interchangeable for forming a composite cam, a part about the axes of said cam-lobes, said last-named part and said respective cam-lobes having graduations and complementary indicating means angularly positioned with relation to said peripheral cam-faces of said cam-lobes for separately adjusting the positions of said separate cam-lobes side by side about the axis of rotation of said cam-shaft for forming depressions of different angular distances between cam-lobes, an operated part coacting with said cam-lobes for moving said slide lengthwise of said axis of said work holding means, and means operating to intermittently rotate said tool-turret during complementary relations of said operated part in said angular spaces.

slide on its said guiding means, and means to operate said constant speed rotating means for said turret during complementary relations of said operated part in said angular spaces.

- 5 20. In a machine of the character described, the combination of a rotatable part, separable cam-lobes provided with holes and having peripheral active cam-faces, graduations and complementary indicating means respectively for said rotatable part and separable cam-lobes, the outer periphery of said rotatable part and the inner periphery of the walls of said respective holes provided with complementary teeth by selective complementary positioning of which about the axis of said rotatable part and selective complementary positioning between said graduations and said complementary indicating means said separable cam-lobes are arranged in angular relation to each other about said rotatable part.

21. In a machine of the character described, the combination of a rotatable part, separable cam-lobes provided with holes and having peripheral active cam-faces, graduations and complementary indicating means respectively for said rotatable part and separable cam-lobes, the outer periphery of said rotatable part and the inner periphery of the walls of said respective holes provided with complementary teeth by selective complementary positioning of which about the axis of said rotatable part and selective complementary positioning between said graduations and said complementary indicating means said separable cam-lobes are arranged in angular relation to each other about said rotatable part; and means for clamping said cam-lobes endwise upon said rotatable part.

- 40 22. In a machine of the character described, the combination with a turret tool-slide, of separable cam-lobes arranged for coaction therewith, a cam-shaft, a rotatable part, means for connecting said cam-shaft and said rotatable part rotatively together, said cam-lobes provided with holes and having peripheral active cam-faces, graduations and complementary indicating means respectively for said rotatable part and separable cam-lobes, the outer periphery of said rotatable part and the inner periphery of the walls of said holes provided with complementary teeth which with selective complementary positioning between said graduations and said complementary indicating means are arranged for relative angular positioning of said respective cam-lobes on said rotatable part, and means for securing said separable cam-lobes to said rotatable part.

60 23. In a machine of the character described, the combination of a turret tool-slide, separable rotatable cam-lobes for coaction with said turret tool-slide, said cam-lobes having peripheral active cam-faces, a part about the axes of said cam-lobes, graduations and com-

plementary indicating means respectively for said part and said separable cam-lobes, a divided cam-shaft, a rotatable part, said rotatable part and said separable cam-lobes provided with complementary positioning means for angular positioning of said respective cam-lobes about the axis of said rotatable part, said rotatable part received between the sections of said cam-shaft in assembling said rotatable part on said cam-shaft, and connecting means between the sections of said cam-shaft.

70 24. In a machine of the character described, the combination of a tool-slide, a cam-shaft, a collar, means rotatively connecting said collar and said cam-shaft, separable cam-lobes provided with holes and having peripheral active cam-faces, graduations and complementary indicating means respectively for said collar and separable cam-lobes, the outer periphery of said collar and the inner periphery of the walls of said holes provided with complementary teeth for angularly positioning said cam-lobes on said collar by selective engagement between said teeth and selective complementary positioning between said graduations and said complementary indicating means, and endwise clamping means clamping said cam-lobes to said collar.

80 25. In a machine of the character described, the combination of a turret tool-slide, separable cam-lobes having peripheral active cam-faces coacting therewith to move said tool-slide, a frame on which said tool-slide is mounted, a separable shaft comprising alined sections, bearings on said frame for the respective sections of said shaft, a collar, graduations and complementary indicating means respectively for said collar and separable cam-lobes, means for selectively angularly securing said cam-lobes on said collar by selective complementary positioning between said graduations and said complementary indicating means for forming said collar and said cam-lobes a composite structure, and 100 means whereby said composite structure is received between the proximate ends of said sections of said cam-shaft in mounting said composite structure on said cam-shaft and removing the same therefrom.

110 26. In a machine of the character described, the combination of a turret tool-slide, separable cam-lobes having peripheral active cam-faces coacting therewith to move said tool-slide, a frame on which said tool-slide is mounted, a separable shaft comprising alined sections, bearings on said frame for the respective sections of said shaft, a collar, graduations and complementary indicating means respectively for said collar and separable cam-lobes, means for selectively angularly securing said cam-lobes on said collar by selective complementary positioning between said graduations and said complementary indicating means for forming said 120 composite structure on said cam-shaft and removing the same therefrom.

125 27. In a machine of the character described, the combination of a turret tool-slide, separable cam-lobes having peripheral active cam-faces coacting therewith to move said tool-slide, a frame on which said tool-slide is mounted, a separable shaft comprising alined sections, bearings on said frame for the respective sections of said shaft, a collar, graduations and complementary indicating means respectively for said collar and separable cam-lobes, means for selectively angularly securing said cam-lobes on said collar by selective complementary positioning between said graduations and said complementary indicating means for forming said 130 composite structure on said cam-shaft and removing the same therefrom.

- collar and said cam-lobes a composite structure, and means whereby said composite structure is received between the proximate ends of said sections of said cam-shaft in
- 5 mounting said composite structure on said cam-shaft and removing the same therefrom, said frame provided with an opening through which said composite structure is moved toward and from said cam-shaft.
- 10 27. In a machine of the character described, the combination of a turret tool-slide, separable cam-lobes having peripheral active cam-faces coacting therewith to move said tool-slide, a frame on which said tool-slide is mounted, a separable shaft comprising alined sections, threading means between said sections for connecting said sections, a collar, graduations and complemental indicating means respectively for said collar and
- 15 20 separable cam-lobes, means for selectively angularly securing said cam-lobes on said collar by selective complemental positioning between said graduations and said complemental indicating means for forming said
- 25 25 collar and said cam-lobes a composite structure, said composite structure received between the proximate ends of said sections of said cam-shaft in mounting said composite structure on said cam-shaft and removing
- 30 30 the same therefrom, and said composite structure clamped between said alined sections by operation of said threading connection.

In testimony whereof, we have hereunto
35 signed our names.

CHARLES HARRY FISCHER.
FREDERICK H. FISCHER.

- collar and said cam-lobes a composite structure, and means whereby said composite structure is received between the proximate ends of said sections of said cam-shaft in mounting said composite structure on said cam-shaft and removing the same therefrom, said frame provided with an opening through which said composite structure is moved toward and from said cam-shaft.
27. In a machine of the character described, the combination of a turret tool-slide, separable cam-lobes having peripheral active cam-faces coacting therewith to move said tool-slide, a frame on which said tool-slide is mounted, a separable shaft comprising alined sections, threading means between said sections for connecting said sections, a collar, graduations and complemental indicating means respectively for said collar and separable cam-lobes, means for selectively angularly securing said cam-lobes on said collar by selective complemental positioning between said graduations and said complemental indicating means for forming said collar and said cam-lobes a composite structure, said composite structure received between the proximate ends of said sections of said cam-shaft in mounting said composite structure on said cam-shaft and removing the same therefrom, and said composite structure clamped between said alined sections by operation of said threading connection.

In testimony whereof, we have hereunto signed our names.

CHARLES HARRY FISCHER.
FREDERICK H. FISCHER.

CERTIFICATE OF CORRECTION.

Patent No. 1,793,279.

Granted February 17, 1931, to

CHARLES HARRY FISCHER ET AL.

It is hereby certified that error appears in the printed specification of the above numbered patent requiring correction as follows: Page 6, lines 44 and 45, and page 7, line 35, for the word "rising" read riding; and that the said Letters Patent should be read with these corrections therein that the same may conform to the record of the case in the Patent Office.

Signed and sealed this 17th day of March, A. D. 1931.

(Seal)

M. J. Moore,
Acting Commissioner of Patents.

CERTIFICATE OF CORRECTION.

Patent No. 1,793,279.

Granted February 17, 1931, to

CHARLES HARRY FISCHER ET AL.

It is hereby certified that error appears in the printed specification of the above numbered patent requiring correction as follows: Page 6, lines 44 and 45, and page 7, line 35, for the word "rising" read riding; and that the said Letters Patent should be read with these corrections therein that the same may conform to the record of the case in the Patent Office.

Signed and sealed this 17th day of March, A. D. 1931.
